UNITED STATES PATENT OFFICE.

JOHN STEWART HARRISON, OF CHARLESTON, SOUTH CAROLINA, ASSIGNEE TO
STANDARD OIL DEVELOPMENT COMPANY, A CORPORATION OF DELAWARE.

PNEUMATIC MULTIPLE PICK.

Application filed May 22, 1925. Serial No. 32,000.

The present invention relates to the art of removing hard material deposited within the interior of a container and more specifically to a means for removing the hard coke-like substance deposited within a vertically disposed chamber, known as a soaking drum, settling tank or the like, by the cracking of hydrocarbons under pressure. The invention will be fully understood from the following description taken in connection with the accompanying drawings which represent diagrammatically a form of apparatus contemplated in the invention and wherein Fig. 1 is a view in section of a container or drum showing my improved pick in operative position within the container; Fig. 2 is a side elevation of the pick, showing internal construction in dotted outline; Fig. 3 is a transverse section on line III—III, Fig. 2; Fig. 4 is a perspective view showing the blades of the pick and the cross-head to which they are attached with a broken section of the casing immediately surrounding the cross-head; and Fig. 5 is a plan of the said cross-head as observed from beneath showing the manner of attachment of the blades thereto.

Referring particularly to the drawings, a chamber or container 1, whose height is great in comparison with its width, has openings 2, 2' at opposite ends thereof which are closed by means of tightly fitting and bolted heads (not shown). After the container has been more or less filled with a deposit 3, such as coke, for example, and the process whereby the deposit is formed has been interrupted, the covers are removed from the openings 2, 2' and a hole 4, of any desired or suitable diameter, is drilled by any suitable means, through the entire depth of the deposit.

40 A pick, operated as hereinafter described, and with its blades in inoperative position, is then lowered by means of a derrick or other hoisting and lowering means through the upper manhole opening 2' and into the hole or 45 channel 4 to a position such that the cutting or picking elements will be somewhat below the upper surface of the deposit.

The pick as ordinarily constructed comprises a casing 5, having a cap 6 fastened 50 tightly thereon. An eye-bolt 7 is fastened to the center of the cap, and a cable 8, which leads to the hoisting and lowering device (not shown), is attached to the eye-bolt.

The casing 5 is bored at its upper end for a 55 suitable distance to accommodate a piston 9.

The lower end 10 of the piston housing is welded to the casing 5 to form a gas tight cylinder 21 for the purpose as hereinafter described.

The piston 9 is attached to a piston rod 11 which operates through a stuffing box 12 kept tight by means of a packing, thus permitting the cylinder 21 to be maintained air or gas tight. The lower end of the piston rod 11 is attached to a cross-head 13 to which are attached the extensible blades 14 of any desired number but preferably four or six in number and preferably arranged approximately at equal angles to one another. Oppositely arranged pairs of blades may be crossed to permit more leverage or may be attached by pins 15 to the cross-head 13 as shown. Guides 13', in the form of plates extending parallel and adjacent to the blades 14, may be arranged in the cross-head 13 to keep each blade approximately in one place. The extensible blades are drawn into and pushed out from the casing by the action of piston rod 11 moving up and down through the stuffing box 12. The casing 5 is slotted at the points 16 where the blades protrude beyond the casing and acts as a guide for the blades themselves. Rollers 18 on arms 17 suitably fastened to the casing 5, are positioned so that the blades protruding through the slots 16 slide over and run on the rollers.

The piston 9 is actuated by fluid means, preferably air, admitted to the cylinder above the piston therein through a connection 19 positioned preferably in the top portion of cap 6. Another connection 20 is provided to deliver air or other fluid or expansive means to the under side of the piston 9 as shown whereby the piston, after it has reached the end of its down stroke, is forced upward to 95 its initial position for starting the down stroke. The air connections are preferably four way manifolds of the well known type which permit the discharge of air from the cylinder both above and below the piston 100 through the same hose that later supplies air to move the piston to its upward or downward position.

The pick, then, with its blades in inoperative position as shown in Fig. 1, is lowered by means of the hoisting device into the channel 4 drilled throughout the depth of the deposit contained within container 1, to a point where the openings through which the extensible blades operate, are ap- 110

proximately one foot below the upper surface of the deposit. Air or other fluid means is then supplied under pressure through connection 19 whereby the piston 9 and piston rod 11 are forced downward. As the piston rod moves downward, the extensible blades 14 ride outward through slots 16 and over the rollers 18 and are forced into the coke 3 or other hard deposit within the container.

10 The piston 9 and the piston rod 11 travel approximately the full length of the cylinder and come to a position of rest with the extensible blades 14 deeply embedded within the deposit. With the air or gas still

15 maintained under pressure within the cylinder above the piston 9, a strain or upward pull is exerted by the hoisting device and the entire pick is pulled upwardly breaking away and dislodging the coke within which the blades are embedded.

20 The coke or other deposit thereupon falls downwardly through the vertical channel previously drilled through the material.

Air is then admitted through the connection 20 into the portion of the cylinder on the underside of the piston 9 which is thereby forced upwardly to its extreme uppermost position. As the piston 9 and piston rod 11 move upwardly, the extensible blades 14 are retracted and withdrawn within the cylinder into an inoperative position. The pick is then lowered again to the position desired in the channel and the operation repeated in the manner as described until the entire deposit of coke has been substantially completely removed from the interior of the container.

Although the description of the process has specifically pointed out a means of removing 40 from a drum the coke produced by the cracking of oils, it is to be understood that the means described are equally applicable to the cleaning out of any difficultly removable solid material which has been deposited or 45 laid down within a container in any manner or by any process.

I claim:

1. In an apparatus for breaking up deposits, the combination of a structure comprising a piston, means for reciprocating the piston, an element connected for extension to

engage the deposit on the movement of the piston in one direction, means for maintaining the extended position of the element, means for elevating the structure while the 55 element is engaged with the deposit whereby the deposit is broken away, and means for retracting the element.

2. In an apparatus for breaking up deposits, the combination of a structure comprising a piston rod, means for reciprocating said rod, a pick operatively connected to the rod and rollers for guiding the picks upon reciprocation of the rod.

3. In an apparatus for breaking up deposits, the combination of a structure comprising a cylinder, a housing within said cylinder, a piston operable within said housing, fluid means for operating said piston, means for delivering said fluid means to said housing, a piston rod connected to said piston and operated thereby, a cross-head attached to said piston rod, a pick connected to the cross-head and guides associated with the pick.

4. In an apparatus for breaking up deposits, the combination of a structure comprising a cylinder, a housing within said cylinder, a piston operable within said housing, fluid means for operating said piston, 80 means for delivering said fluid means to said housing, a piston rod connected to said piston and operated thereby, a cross-head attached to said piston rod, and a pick pivotally connected to said cross-head, said pick being extended into operating position by the downward movement of the piston.

5. In an apparatus for breaking up deposits, the combination of a structure comprising a cylinder, a housing within said cylinder, a piston operable within said housing, air connections for delivering air under pressure to said housing to operate the piston therein, a piston rod connected to said piston and operated thereby, a cross-head attached to said piston rod, and picks pivotally connected to said cross-head, said picks being extended through slots in said cylinder into an operating position by the downward movement of the piston.

JOHN STEWART HARRISON.
